UNITED STATES PATENT OFFICE.

JOHN B. MULLALLY, OF SEATTLE, WASHINGTON.

ENVELOP-MOISTENER.

1,313,723.

Specification of Letters Patent. Patented Aug. 19, 1919.

Application filed July 31, 1918. Serial No. 247,625.

To all whom it may concern:

Be it known that I, JOHN B. MULLALLY, a citizen of the United States, and resident of the city of Seattle, county of King, and 5 State of Washington, have invented certain new and useful Improvements in Envelop-Moisteners, of which the following is a specification.

My invention relates to devices which are 10 designed for use for moistening envelops, stamps and other articles which are provided with an adhesive coating and consists of certain combinations of parts which will be hereinafter described and then particularly pointed out in the claims.

The object of my invention is to provide a device which will hold an absorbent pad or sponge, and which may be secured upon the hand at the back and base of the fingers, 20 so as to be in convenient position for sweeping over the gummed edge of an envelop at the time the letter is placed therein.

In the accompanying drawings I have shown my invention in two forms of construction, the same being in principle much 25 the same and illustrating my present preferred forms of construction.

Figure 1 is a side view of my device with a portion of the front wall of the pad-holder 30 broken away.

Fig. 2 is a front view of the device, showing it as set within a holding cup.

Fig. 3 is a side view of a modified construction shown in place on the hand. 35 In constructing my device I provide a holder for a sponge or absorbent pad, which sponge or pad is held thereby with a portion projecting therefrom, so that it may be applied to the gummed surface for the purpose of moistening the same. I also provide rings or eyes attached, to receive fingers of the hand, so that the device may be supported at the back of the hand, preferably well down toward the base of the fingers. 45

The pad 1, as herein illustrated, is supposed to consist of a small sponge. This is inserted within the holder 2, which, in the construction shown in Figs. 1 and 2, 50 consists of a small cup or cylinder, which is open at its lower end. Preferably it is closed at the other end, although this is not essential.

Connected with the cup or holder 2, are 55 the finger receiving rings 3 and 4. These rings are connected in suitable construction,

as by the bar 5. These rings may be made of wire or of a narrow strip of sheet metal, as preferred. This should be secured to the holder in about the relation shown in 60 Figs. 1 and 2, that is, one of the rings, as the ring 3, should be at about the level of the holder, while the other ring, 4, should be at a higher elevation. The object of separating the rings is to provide a firmer 65 support from the hand. If a single ring were used there would be a strong tendency for the device to rock or roll over, as it is used. Where two or more fingers are engaged this rocking action is very largely 70 reduced.

I prefer to separate these rings so that they will engage non-adjacent fingers, as for instance, the first and third fingers of the hand, as is shown in Fig. 3. These finger-receiving rings are placed in an axial plane 75 of the holder, so that when the device is placed upon the hand the axis of the holder extends crosswise of the fingers.

In Fig. 3 a modified construction is shown 80 in which the holder is made of a wire 6, coiled in the form of a helix into which one end of the sponge is pressed. In this case the rings 3 and 4 are formed by simply bending the ends of the wire. 85

In Fig. 2 I have shown a cup 6 which has a tubular upward extension 60 of sufficient size to easily receive the sponge 1 and its holder. This is slotted on one side to permit passage of the ring 3. The moistening device 90 may be supported, in part at least, either by the engagement of the ring with the bottom of the slot, or with the top of the cup. Within the cup is an absorbent mass 61 of cotton, sponge, felt, or like material, which 95 is kept well moistened and from which the pad 1 absorbs moisture, so that it is at all times in suitably moist condition for use.

If, in taking the device out of its cap or holder, the sponge is too wet, it may be 100 squeezed between the thumb and fingers, to extract the surplus moisture. The direction of pressure would be in the direction of the axis of the holder 2 or 6 of the respective forms shown. In the form shown in Fig. 105 3, the coil 6 which forms the sponge holder would have sufficient resiliency to be axially compressible and expandable, so that it will return to its normal position.

In using my device it is placed upon the 110 hand in the manner shown in Fig. 3. As the envelops are placed upon the table with

- the flap folded out and with the addressed side down, the letter is slipped therein. The moistener should be placed upon the hand which is used for the insertion of the letter.
- 5 When the letter is inserted the hand is then given a slight sweep which carries it over the gummed edge of the letter and the flap is then folded down. The device while on the hand, does not interfere in any way with 10 any of the work being done. It is light, cheap to manufacture, and is very convenient for use.
- What I claim as my invention is:
1. An envelop moistener comprising a 15 holder for a moistening pad, and means for securing it at the back of the fingers at their base with the moistening surface of the pad extending outwardly from the finger backs.
  2. An envelop moistener comprising a 20 holder for a moistening pad and finger receiving rings adapted to receive a plurality of fingers.
  3. An envelop moistener comprising a 25 holder for a moistening pad and a finger receiving loop secured thereto and adapted to hold the operating face of the pad at the back of and substantially in the plane of the outer edge of the little finger side of the hand.
  - 30 4. An envelop moistener comprising an absorbent body and a holder therefor provided with means for engagement by the fingers to support said absorbent body at the back of the base of the fingers.
5. An envelop moistener comprising an 35 absorbent body and a holder therefor having rings for the reception of a plurality of the fingers of the hand.
6. An envelop moistener comprising an 40 absorbent body and a holder therefor having two finger receiving rings separated to receive non-adjacent fingers.
7. An envelop moistener comprising an 45 absorbent body and a holder therefor provided with rings for receiving a plurality of fingers.
8. An envelop moistener comprising an 50 absorbent body, a holder for said body, and a plurality of finger receiving rings lying in an axial plane of said holder.
9. An envelop moistener comprising a 55 compressible absorbent body and a holder therefor which is also compressible and contains means for securing it to the fingers and at the back thereof.
10. An envelop moistener comprising an 60 absorbent pad, a holder formed of a coiled resilient wire, said wire also having finger receiving eyes formed therein.
11. An envelop moistener comprising a 65 compressible holder for a moistening pad, and means for securing it at the back of the fingers at their base with the moistening surface of the pad extending outwardly from the finger backs.

Signed at Seattle, Washington, this 26th day of July, 1918.

JOHN B. MULLALLY.
